(57) **ABSTRACT**

A package for holding a compact disc (CD). The package is defined by a unitary package piece that is divided into a set of sections, and each of the set of sections is capable of having printed data thereon. The unitary package piece includes a CD holding section defined by a section of the unitary package piece. The CD holding section having a pair of CD support flaps and a CD access cut-out. A set of four sections are part of the unitary package piece, and the set of four sections are defined by a first fold line and a second fold line. The CD holding section is configured to fold and adhere to one of the set of four sections, and the set of four sections are configured to define the package when folded along the first fold line and the second fold line. A locking flap is integral with one of the four sections of the unitary package piece, and the locking flap is configured to hold the package together when folded along the first fold line and the second fold line.

COMPACT DISC PACKAGE SYSTEM AND METHODS FOR PACKAGING THE SAME

BACKGROUND OF THE INVENTION

1. Field of the Invention

The present invention relates to packaging and, more particularly, to a package and a method for packaging software media containing a software application.

2. Description of the Related Art

Software applications are typically delivered to original equipment manufacturers (OEMs) on a computer readable media such as, for example, a compact disc (CD). The computer readable media is typically accompanied by documentation for the end user such as, for example, a registration card, a copyright disclaimer card, and a product information guide. In one known method for packaging software applications for delivery to OEMs, a CD having the software application stored thereon is individually packed along with the accompanying documentation in an envelope-like package. Once verification that the proper inserts have been placed in the package, the package is securely sealed. Thereafter, the package is shipped to an OEM so that the software application can be either installed on or shipped with a computer or other board product.

Although the process is rather straight forward, labor overhead is necessary to ensure that each of the inserts are properly placed in the package, and the correct version documentation is applied to the package. If a version change occurs, the CDs must be replaced with new CDs. In some cases, some of the inserts will be reused, while others may be version specific, and therefore must be thrown away. In any case, the envelope will not be reused, since opening the packing envelope will also damage the envelope.

In view of the foregoing, what is needed is a package for packaging a compact disc that efficiently accommodates frequent changes in software recorded on the compact disc, while enabling reuse of substantially all of the original packing material.

SUMMARY OF THE INVENTION

Broadly speaking, the present invention fills this need by providing a package and method for cost effectively packaging a compact disc (CD) containing computer readable data. The package is also configured for easy reuse by simply removing a shrink-wrapping, replacing the CD, and re-shrink-wrapping the package. A label can then be applied to the shrink-wrap. In one aspect of the invention, all text or graphics are applied directly to the package, thus obviating the need for separate inserts and additional labor needed to manage the packing process.

In accordance with one aspect of the present invention, a package for holding a compact disc (CD) is provided. The package is defined by a unitary package piece that is divided into a set of sections, and each of the set of sections is capable of having printed data thereon. The unitary package piece includes a CD holding section defined by a section of the unitary package piece. The CD holding section having a pair of CD support flaps and a CD access cut-out. A set of four sections are part of the unitary package piece, and the set of four sections are defined by a first fold line and a second fold line. The CD holding section is configured to fold and adhere to one of the set of four sections, and the set of four sections are configured to define the package when folded along the first fold line and the second fold line. A

locking flap is integral with one of the four sections of the unitary package piece, and the locking flap is configured to hold the package together when folded along the first fold line and the second fold line.

5 A package for holding a compact disc (CD) containing software for shipping is disclosed. The package is defined from a unitary package piece that is divided into a set of sections, and each of the set of sections is capable of having printed data thereon. The unitary package piece includes a CD holding section defined by a section of the unitary package piece, and the CD holding section has a pair of CD support flaps and a CD access cut-out. A set of four sections are part of the unitary package piece, and the set of four sections is defined by a first fold line and a second fold line. The CD holding section is configured to fold and adhere to one of the set of four sections, and the set of four sections are configured to define the package when folded along the first fold line and the second fold line. A locking flap is further configured to be integral with one of the four sections of the unitary package piece, and the locking flap is configured to hold the package together when folded along the first fold line and the second fold line. Further provided is an adhesive for holding the pair of CD support flaps against the one of the set of four sections of the unitary package piece, and an insert cut is defined into one of the set of four sections. The insert cut is configured to receive the locking flap to hold the package together in a closed state.

10 It is to be understood that the foregoing general description and the following detailed description are exemplary and explanatory only and are not restrictive of the invention, as claimed.

BRIEF DESCRIPTION OF THE DRAWINGS

The accompanying drawings, which are incorporated in and constitute part of this specification, illustrate exemplary embodiments of the invention and together with the description serve to explain the principles of the invention.

15 FIG. 1A illustrates an unfolded unitary package 100 for holding a compact disc (CD) for shipping software, in accordance with one embodiment of the present invention.

20 FIG. 1B illustrates the folding of CD support flaps, in accordance with one embodiment of the present invention.

25 FIG. 2A illustrates the CD package after a section has been folded over and caused to adhere to another section using an adhesive, in accordance with one embodiment of the present invention.

30 FIG. 2B illustrates the CD package after it has been folded along a fold line, in accordance with one embodiment of the invention.

35 FIG. 2C illustrates the final folding of the CD package before a locking flap is activated, in accordance with one embodiment of the present invention.

40 FIGS. 3A-3E illustrate the process of inserting a CD into the CD package, the serial number marking process, the shrink-wrap process, and the final product marking process, in accordance with one embodiment of the present invention.

45 FIG. 4 illustrates yet another packing embodiment, in accordance with one embodiment of the present invention.

50 FIG. 5 is a flowchart illustrating the versatility of the CD package, in accordance with one embodiment of the present invention.

DETAILED DESCRIPTION OF THE INVENTION

55 Several exemplary embodiments of the invention will now be described in detail with reference to the accompanying drawings.

FIG. 1A illustrates an unfolded package **100** for holding a compact disc (CD) for shipping software, in accordance with one embodiment of the present invention. As shown, the unfolded package **100** has a number of package sections **102a**, **102b**, **102c**, **102d**, **102e**, **102f-1**, **102f-2**, and **102g**. Each of the package sections is defined from a unitary piece of material, thus defining a unitary package piece. In one embodiment, the material is a thick paper material having a degree of rigidity, yet capable of being folded. As shown, the unfolded package **100** also includes a number of cut-outs **104a**–**104d**. Also provided is a CD access cut-out **105** to allow access to the CD once the package is assembled. To ensure that the resulting CD package has the desired shape, edge cuts **106a**–**106d** are provided. For instance, the edge cuts **106a**–**106d** allow the finished CD package to have slightly rounded corners, as opposed to sharp edges. The rounding of the corners, as will be explained below, will allow the CD package to be shrink-wrapped with better ease, thus avoiding premature cutting of the shrink-wrap.

FIG. 1B illustrates the folding of CD support flaps **102f-1** and **102f-2**. Once the CD support flaps **102f-1** and **102f-2** are folded down and against section **102e**, which has a cut-out section **102e'**, an adhesive **206** is applied to the folded CD support flaps **102f-1** and **102f-2**. The adhesive **206** will thus allow the CD support flaps **102f-1** and **102f-2** to stay joined to respective parts of the section **102d**, once folded along fold line **203**. Also illustrated are fold lines **202** and **204**, each assisting to divide sections **102a**, **102b**, **102c** and **102d**. To provide for smoother folds along fold line **204**, a cut-out **104e** is defined along part of the fold line **204**.

FIG. 2A illustrates the CD package after the section **102e** has been folded over and caused to adhere to section **102d** using the adhesive **206**. This view also illustrates that the packaging material is not only used to pack the CD for shipping, but also for applying text, graphics, and the like directly on the package. In one embodiment, the CD package is essentially complete once the section **102e** is adhered to section **102d**, since the CD can be held within the pouch created by the adhered folded section **102e**. In practice, the end user of the CD, at the time of unpacking, will be able to unfold the CD package **210** at the point shown in FIG. 2A. Although not shown from this view, text and graphics can also be applied to the reverse side of the package. As used herein, the text and graphics can be used to replace the printed material inserts, such as instructions, license, and other OEM and vendor information. Beneficially, there will be no need to insert separate packing materials or employ additional labor to complete the packing process.

FIG. 2B illustrates the CD package **210** after it has been folded along fold line **202**. This illustration shows how additional instructions can be written inside of the CD package **210**. Essentially, FIG. 2B illustrates the reverse sides of section **102a** and **102b**, leaving fold line **204**. All along, locking flap **102g**, remains open awaiting the final fold along fold line **204**. Once the fold along fold line **204** is complete, additional graphics, logos, text or instructions can be printed on the backside of section **102c**. Also evident from the perspective of FIG. 2C is the insert cut **108**. The insert cut **108** will be used to receive the locking flap **102g** at the final stage of folding. It should be noted that the folding that occurred between in FIGS. 2B and 2C are not permanent, thus enabling reuse of the CD package **210**. For instance, assuming that the CD needed to be replaced with a new application version, the software originator can simply: (a) unlock the folding flap **102g**, and (b) slide out the CD from within the pouch created by sections **102d**, **102e**, and CD support flaps **102f-1** and **102f-2**. Once removed, a

new CD can be inserted and the folding flap **102g** can be re-inserted into the insert cut in section **102c**.

Alternatively, the originator can, in addition to (a) unlocking the folding flap **102g**, the package can be unfolded at fold lines **204** and **202**. This will also expose all of the text, graphics and the like. Assuming that the text, install instructions, and license are the same for the new version, the entire CD package **210** can be reused. Furthermore, it is emphasized that the embodiments of the present invention also enable more efficient initial assembly of packing materials, which beneficially lowers packing labor costs.

FIGS. 3A–3E illustrate the process of inserting a CD into the CD package **210**, serial number marking process, shrink-wrap process, and the final product marking process. As shown in FIG. 3A, a CD **212** is shown being inserted into a CD package **210**. In this example, the CD **212** is inserted with the CD package **210** having its locking flap **102g** undone. As the CD **212** is slid into the CD package **210** (to be held within the pouch created by sections **102d**, **102e**, and **102f-1** and **102f-2**), the locking flap **102g** remains open. In FIG. 3B, the locking flap **102g** is folded over and caused to be inserted into the insert cut **108**. Once inserted, the locking flap **102g** will keep the CD **212** contained within the CD package **212**. FIG. 3C illustrates how the serial number **220** of the software written to the CD **212** is applied directly to the CD package **210**. In one embodiment, the serial number will remain the same, no matter if update versions are to be shipped in the same package. Thus, the serial number can be directly applied to the CD package **212**, without the need to remove the same.

In FIG. 3D, the CD package **212** is processed through a shrink-wrap machine. The shrink-wrapping **230** will ensure that the CD package **212** will only be opened by a consumer that intends to abide by the shrink-wrapping license. Once the shrink-wrapping **230** is applied, a product label **240** is applied to the shrink-wrapping. Because the product label **240** will change depending on the version being shipped in the CD package **210**, the product label **240** will not be adhered directly to the CD package **210**, which can damage the appearance if removed (e.g., by pealing off and the like).

FIG. 4 illustrates yet another packing embodiment, in accordance with one embodiment of the present invention. As shown, packed CDs, such as those illustrated in FIG. 3E, can then be efficiently bulk packaged in a carton **302**. To efficiently pack the CDs **212**, a layer pad **306a** is first placed into the base of the carton **302**. A layer pad **306b**, is then placed between rows of CD packages **210**. In one embodiment, 50 pieces of packaged CDs are placed in each of the two rows. In a preferred embodiment, the locking flaps **102g** are placed facing the layer pad **306b**. Once the CDs **212** have been placed into the carton **302**, a layer pad **306c** is placed over the CDs **212**. Carton flaps **304** are then closed and subject to sealing. The carton **302**, holding 100 packaged CDs, can then be shipped to a recipient.

FIG. 5 is a flowchart **350** illustrating the versatility of the CD package **210**, in accordance with one embodiment of the present invention. Flowchart **350** illustrates a method for reusing a CD package **210** which holds a CD having dated software, thus needing an upgraded version of the software by way of a replacement CD. Assuming a CD package **210** has been previously packaged as discussed in FIGS. 1–4, the method in operation **352** proceeds to where the shrink-wrapping is removed from the CD package. In operation **354**, the locking flap is opened to allow access to the CD. In operation **356**, the current CD is removed from the CD package **210**. If desired, the CD package **210** can be

unfolded as discussed above, or can simply be opened to allow removal of the CD by opening the locking flap. In operation 358, a new CD is inserted into the CD package. The new CD, in one embodiment, can represent the CD containing upgraded software or new data. For purposes of clarity, the CD can contain any type of date, whether it be audio, software code, or user data.

In operation 360, once the new CD is inserted into the CD package 210, the locking flap is folded to close the package containing the new CD. In operation 362, shrink-wrapping is applied to the CD package 210 containing the new CD. Finally, an updated product label is applied to the shrink-wrapping, for example, to apply an OEM product label (e.g., containing a product part number and revision). At this point, the reused CD package 210 can individually be shipped to an end user, e.g., an OEM, or can be packed into a carton for bulk shipping.

It should be noted that the packaging methodology of the present invention enables very efficient reuse of the entire CD package 210. Notably, any instructions on use of the packed CD can be printed directly onto the CD package. To provide additional space for the documentation, the CD package 210 can be printed on a number of sides, both internal and external. This therefore eliminates the need to separately pack instruction materials, license documentation, and the like. Having less inserts provides for more efficient use of labor to complete the CD package or reuse the CD package once an upgrade is needed. Also important to note is that the CD package can be reused any number of times, so long as the instructions and/or license printed on the package itself are current. The product label 240, which does change with version number, is conveniently applied to the shrink-wrapping, which is replaced anytime an upgrade occurs.

The invention has been described herein in terms of several exemplary embodiments. Other embodiments of the invention will be apparent to those skilled in the art from consideration of the specification and practice of the invention. The embodiments and preferred features described above should be considered exemplary, with the invention being defined by the appended claims.

What is claimed is:

1. A package, comprising:

a unitary package piece being divided into a set of sections, each of the set of sections capable of having printed data thereon, the unitary package piece including,

a CD holding section defined by a section of the unitary package piece, the CD holding section having a pair of CD support flaps and a CD access cut-out;

a set of four sections all joined together and being part of the unitary package piece, the set of four sections being defined by a first fold line and a second fold line, and the first fold line being perpendicular to, and intersecting through the second fold line, and the CD holding section being configured to fold and adhere to one of the set of four sections, the set of four sections being configured to define the package when folded along the first fold line and the second fold line; and

a locking flap being integral with one of the four sections of the unitary package piece, the locking flap being configured to hold the package together when folded along the first fold line and the second fold line.

2. The package as recited in claim 1, further comprising:

an adhesive for holding the pair of CD support flaps against the one of the set of four sections of the unitary package piece.

3. The package as recited in claim 2, further comprising: an insert cut defined into one of the set of four sections, the insert cut being configured to receive the locking flap to hold the package together in a closed state.

4. The package as recited in claim 2, further comprising: a shrink-wrap cover, the shrink-wrap cover being configured to contain the package and prevent access to the locking flap without cutting the shrink-wrap cover.

5. The package as recited in claim 4, further comprising: a label being attached to the shrink-wrap.

6. The package as recited in claim 1, further comprising: a compact disc configured to be held within the package.

7. The package as recited in claim 1, wherein the printed data is configured to replace package inserts, such that no literature insert is contained in the package.

8. The package as recited in claim 1, wherein the unitary package piece, when folded along the first fold line and the second fold line, is about the size of a compact disc.

9. The package as recited in claim 4, wherein a plurality of packages made from the unitary package piece containing compact discs are further packaged into a carton.

10. A compact disc package, comprising:

a unitary package piece being divided into a set of sections, each of the set of sections capable of having printed data thereon, the unitary package piece including,

a CD holding section defined by a section of the unitary package piece, a set of four sections all joined together and being part of the unitary package piece, the set of four sections being defined by a first fold line and a second fold line, and the first fold line being perpendicular to, and intersecting through the second fold line, and the CD holding section being configured to fold and adhere to one of the set of four sections, the set of four sections being configured to define the package when folded along the first fold line and the second fold line; and

a locking flap being integral with one of the four sections of the unitary package piece, the locking flap being configured to hold the package together when folded along the first fold line and the second fold line.

11. A compact disc package as recited in claim 10, further comprising:

a pair of CD support flaps defined in the CD holding section.

12. A compact disc package as recited in claim 10, further comprising:

a CD access cut-out being defined in the CD holding section.

13. A compact disc package as recited in claim 10, further comprising:

an adhesive for holding a pair of CD support flaps against the one of the set of four sections of the unitary package piece.

14. A compact disc package as recited in claim 13, further comprising:

an insert cut defined into one of the set of four sections, the insert cut being configured to receive the locking flap to hold the package together in a closed state.

15. A compact disc package as recited in claim 14, further comprising:

a shrink-wrap cover, the shrink-wrap cover being configured to contain the package and prevent access to the locking flap without cutting the shrink-wrap cover.

- 16.** A compact disc package as recited in claim **15**, further comprising:
a label being attached to the shrink-wrap.
- 17.** A compact disc package as recited in claim **10**, further comprising:
a compact disc configured to be held within the package.
- 18.** A compact disc package as recited in claim **10**, wherein the printed data is configured to replace package inserts, such that no literature insert is contained in the package.
- 19.** The package as recited in claim **10**, wherein the unitary package piece, when folded along the first fold line and the second fold line, is about the size of a compact disc.
- 20.** A package for holding a compact disc (CD) containing software for shipping, comprising:
a unitary package piece being divided into a set of sections, each of the set of sections capable of having printed data thereon, the unitary package piece including,
a CD holding section defined by a section of the unitary package piece, the CD holding section having a pair of CD support flaps and a CD access cut-out;

- a set of four sections all joined together and being part of the unitary package piece, the set of four sections being defined by a first fold line and a second fold line, and the first fold line being perpendicular to, and intersecting through the second fold line, and the CD holding section being configured to fold and adhere to one of the set of four sections, the set of four sections being configured to define the package when folded along the first fold line and the second fold line;
- a locking flap being integral with one of the four sections of the unitary package piece, the locking flap being configured to hold the package together when folded along the first fold line and the second fold line;
- an adhesive for holding the pair of CD support flaps against the one of the set of four sections of the unitary package piece; and
- an insert cut defined into one of the set of four sections, the insert cut being configured to receive the locking flap to hold the package together in a closed state.
